UNITING SPIDER STRUCTURE

William Francis Moore, New Haven, Conn., assignor to The A. C. Gilbert Company, New Haven, Conn., a corporation of Maryland

Application October 5, 1950, Serial No. 188,523

11 Claims. (Cl. 230—132)

1

This invention relates to structure for uniting in rigid relationship a motor body carrying an electric fan impeller and a stationary funnel shell that surrounds the impeller blades and guides the air stream of the fan, whereby either the motor body or the funnel shell may derive firm support from the other.

One object of the invention is to centralize in firmly fixed relationship a motor body and an encompassing funnel shell of considerably larger compass than the motor body by the use of coupling structure that impedes as little as possible the flow of air through the annular space between the motor body and funnel shell.

A further object is to make use of bent sheet metal connecting parts radially spanning the aforesaid annular space.

A further object is to attach radially disposed sheet metal plates to a motor body without the use of fastening screws.

A further object is to fasten radially disposed supporting fins to a hollow encompassing shell ring in a manner to deaden the transmission of vibration from one sheet metal part to another.

A further object is to utilize circuitous or circular wire rings as binding elements for angularly related fin plates when radially directed toward a common center, and also to serve as a safeguard against entrance of foreign objects into the annular space spanned by such fin plates.

The foregoing and other objects of the invention will appear in greater particular from the following description of a successful embodiment of the invention having reference to the accompanying drawings wherein:

Fig. 1 is a rear view of an electric household fan having the body of its electric motor held centrally of a funnel shell by structure embodying the present invention.

Fig. 2 is a view taken partly in section on the plane 2—2 in Fig. 1.

Fig. 3 is a side view of the fan of Fig. 1 showing the air blowing unit of Fig. 2 swung to a vertical instead of a horizontally facing position.

Fig. 4 is an enlarged fragmentary view of one of the radially support fins with its connections to the motor body and ring shell which it serves to unite.

Fig. 5 is a view taken on the plane 5—5 in Fig. 4 looking toward the motor body in the direction of the arrows.

Since the features with which the present invention is most closely concerned have to do more particularly with the structure whose de-

2

tails are shown in Figs. 4 and 5, it will suffice to describe the supporting standard and stationary frame of the fan as comprising a hollow base 12 incorporating a dished top wall 14 to which is fixed a rigid circular frame ring 18. The bottom edge of base 12 carries foot discs 20 of non scarring material on which base 12 stands. In the hollow of the base there is an electric switch controlling the supply of current derived through attachment cord 26. The handle of this switch is a turnable knob 24 accessible at the front exterior of the base. A flexible wire cable leads switch controlled current from the base to a fan motor 54.

A fan motor 54, air impeller 55 having blades 90 and funnel shell structure 28 are swingably mounted as a unit on a surrounding frame ring 18 so as to be turnable about the horizontal axis of hinge pins 42 which penetrate hinge studs 32

fixed to the frame ring. The swingable structure is maintained in selected positions to which it may be adjusted by detent means not herein shown but disclosed and claimed in a copending application, Serial No. 188,524, filed October 25, 1950, now Patent No. 2,660,368, issued November 24, 1953. Features of the fan motor, air impeller and funnel shell constructions are disclosed and claimed in another copending application, Serial No. 195,210, filed November 13, 1950.

The funnel shell structure viewed as an integral unit is composed of two drawn sheet metal parts forming a hollow annulus. The circumferentially inner part provides an air stream guiding conduit 46 while the circumferentially outer part forms a casing 44 whose circular edges overlap and form a rigid joint with circular edges of the conduit shell 46.

The front opening of casing shell 44 and funnel shell 28 is spanned by grid 48 having the cross vanes 52 and whose border rim is removably secured by screws 50 to the casing shell.

The problem solved by the present invention concerns the rigid uniting of motor 54 with the conduit shell 46 so that the fan impeller 55 is constrained to rotate in accurate pre-determined fixed relation to the funnel structure 28 shown in Fig. 2. For this purpose there are provided four stiff flat fin plates 56 each of somewhat triangular shape delineated by two diverging edges spanning the annular gap or air passageway between the motor casing 60 and conduit shell 46. Fin plates 56 are radially disposed and aligned with planes containing the axis of rotation of the impeller and have flanges 58 turned over in respectively opposite directions and bearing against the

outer surface of the motor housing 60. Also there are alignment tongues 62 on fin plates 56 which penetrate close fitting slots in the motor housing 60. The radially outermost extremity or apex of each fin plate 56 is bent over at right angles at 63 and is equipped with a vibration absorbing bushing 64 through which extends a mounting screw 66 which also extends through a close fitting hole in the funnel-shaped wall of air conduit 46. Screw 66 threads into a holding nut 68 that is fixed in place within the hollow annular space between conduit wall 46 and casing wall 44 of the funnel structure 28. The triangular shape of the flat fin plates and the fixed attachment of their innermost or base edge to the motor body imparts to the plate minimum weight combined with maximum cantilever strength and these plates braced by hoops 70, 72 and 74 form a mounting spider in which the holes in plate extremities 58 are maintained in relative positions to register respectively with the matching holes in shell 46 for screws 186 in the absence of such screws and during any period when the spider remains detached from the shell.

Fins 56 are evenly spaced about the motor body and are fixed thereto as previously described with the strengthening assistance of three wire hoops 70, 72, and 74, of increasing diameter in the order named, these hoops being nested in notches in the edges of the fin plates and securely retained therein by slightly bent-over projecting lips 75.

In assembling the structure hereinbefore described the tongues 62 of each fin plate will be inserted through their close fitting slots in motor housing 60 until the plate flanges 58 abut against the outer surface of the motor housing, to the wall of which housing these flanges can then be spot welded or otherwise firmly fastened. There will be inserted in a hole in the bent-over apex 63 of each fin plate eyelet grommet 64 of distortable resilient rubber. The fin plate tongues 62 may be inserted in the motor housing slots while the notches in their sloping edges are occupied by the crosswise encompassing wire hoops 70, 72, and 74. Notch bordering projecting lips 75 at that time stand straight as indicated by broken lines in Fig. 4. The fin plates may be tilted out of radial alignment with the axis of the motor when initially introducing their tongues 62 into their slots in the motor housing 60 after which all the fin plates can be swung into true radial alignment so as to cause the plates edges to wedge somewhat between the wire hoops 70, 72, and 74 and the motor housing thus taking up all initial looseness or play therebetween. For further increasing the security with which the wire hoops are lodged in the plate notches, the projecting lip 75 that flanks each notch is forced toward the left in Fig. 4, thus partly closing the mouth of the notch while clinching against the wire of the hoop.

The four fin plates 56 are then removably fastened to the funnel shell structure 28 by inserting holding screws 66 through the grommets 64 and through registering clearance holes in the sheet metal of conduit shell 46 into threaded engagement with the nuts 68, respectively, that may be welded to the surface of the conduit shell before it is assembled with the casing shell 44 to form the hollow annular funnel shell structure 28.

The appended claims are directed to and cover all fair equivalents for the parts and their relationships that are herein disclosed to explain a

successful embodiment of the principles of invention and are intended to be given the broadest interpretation applicable to their wording.

I claim:

5. Mounting structure for assembling in coaxial readily separable relation the motor body of an electric fan and a funnel shell that surrounds the fan, comprising in combination with said body and shell, a mounting spider of skeleton construction occupying the annular space between said body and shell including plates radiating in the manner of fins from the motor body, each of said plates having a radially innermost edge elongated in the direction of the motor axis fixedly attached to the motor body, and each of said plates having another edge spanning the annular space between said body and shell terminating at a radially outermost extremity of the plate, matching elements on said shell and on said plate extremities, means to fasten said elements detachably together, and at least one plate bracing hoop surrounding the motor body at a radius intermediate said innermost plate edges and said plate extremities fixedly attached to said space spanning edges of said plates in a manner to maintain said matching elements on the plate extremities in relative position to register respectively with said elements on the shell in the absence of said fastening means.
10. 2. Mounting structure as defined in claim 1, in which each of the said plates is flat and has still another edge also spanning the said annular space between the said motor body and the said funnel shell and also terminating at the said extremity of the plate, the two said space spanning edges of the plate diverging to meet the said innermost edge of the plate at locations spaced well apart axially of the motor body wherefore to delineate a generally triangular shape of plate based on the motor body whereby there is imparted to the plate minimum weight combined with maximum cantilever strength.
15. 3. Mounting structure as defined in claim 1, in which the said space spanning edges of the said plates respectively contain notches located in a common plane perpendicular to the axis of the motor, in all of which notches the said bracing hoop is firmly lodged.
20. 4. Mounting structure as defined in claim 1, in which the said space spanning edges of the said plates are inclined with respect to the motor axis in directions to face outwardly away from the said motor body, and the said bracing hoop girdles the said inclined plate edges in crosswise relation thereto.
25. 5. Mounting structure as defined in claim 1, in which the said space spanning edges of the said plates are inclined in respect to the motor axis in a direction to face outwardly away from the said motor body and contain notches located in a common plane perpendicular to the motor axis, said inclined edges being girdled by the said plate bracing hoop and said hoop occupying said notches.
30. 6. Mounting structure as defined in claim 1, in which the said space spanning edges of the said plates respectively contain notches flanked by a lip delineated by the contour of said edge and occupied by the said bracing hoop, said lips being bent inward toward said notches respectively in a manner to clinch said hoop while the latter is lodged in said notches.
35. 7. Spider structure as defined in claim 1, in which there are a plurality of the said hoops spaced apart and of differing compass each gir-

dling and binding all of the said fin plates together.

8. Spider structure as defined in claim 1, in which the said elongated innermost edge of each of said fin plates carries at least one straight tongue and at least one bent over flange, and the said motor body contains at least one opening occupied and closely filled by said tongue, said bent over flange bearing against and being secured to the external surface of said motor body. 10

9. Mounting structure as defined in claim 1, in which one of said matching elements includes a flange on the said radially outermost extremity of each of the said plates paralleling the inner surface of the said funnel shell and containing a hole 15 registering with a hole in said shell, and the said fastening means includes a holding screw extending through both of said holes having its axis in parallel relation to the plate.

10. Spider structure as defined in claim 9, together with a vibration absorptive grommet of resilient material sufficiently distortable within its elastic limit to be forced into occupancy of one of the said holes surrounding the said holding screw and completely separating it from metallic contact with the said flange of the said plate. 20 25

11. The method of assembling a spider support structure in an annular space between a supported fan body and an encompassing annular support, which includes the steps of placing fin plates about the said fan body each in broadside tilted relation to a different radial plane containing the axis of the fan, engirdling said fin plates with a hoop, and then righting said fin plates into alignment respectively with said radial planes against the constraining resistance of said hoop.

WILLIAM FRANCIS MOORE.
